US00D554384S

(12) **United States Design Patent** (10) **Patent No.:** **US D554,384 S**
(45) **Date of Patent:** **** Nov. 6, 2007**

(54) **CHAIR**

(75) Inventors: **Robert Scheper**, Souffelweyersheim (FR); **Glen Oliver Loew**, Hamburg (DE)

(73) Assignee: **Steelcase Development Corporation**, Caledonia, MI (US)

(**) Term: **14 Years**

(21) Appl. No.: **29/277,055**

(22) Filed: **Feb. 12, 2007**

Related U.S. Application Data

(62) Division of application No. 29/214,446, filed on Oct. 1, 2004.

(30) **Foreign Application Priority Data**

Jun. 7, 2004 (FR) 191457

(51) **LOC (8) Cl.** **06-01**

(52) **U.S. Cl.** **D6/374**

(58) **Field of Classification Search** D6/374, D6/372, 375, 334, 502, 498, 499; 297/411.27, 297/452.29, 451.4, 451.5, 451.6, 452.14, 297/448.2

See application file for complete search history.
